DESIGN FOR A PORTABLE SHELF UNIT

Meyer M. Miller and Lottie K. Miller,
Baltimore, Md.

Application February 20, 1946, Serial No. 126,758

Term of patent 14 years

(Cl. D33—14)

To all whom it may concern:

Be it known that we, Meyer M. Miller and Lottie K. Miller, citizens of the United States of America, residing in Baltimore, State of Maryland, have invented a new, original, and ornamental Design for a Portable Shelf Unit, of which the following is a specification, reference being had to the accompanying drawing, forming part thereof, in which:

We claim:

The ornamental design for a portable shelf unit, substantially as shown.

MEYER M. MILLER.
LOTTIE K. MILLER.
